GAME BOARD AND PLAYING PIECES

Charles S. Horine, Lexington, Ky.

Application August 12, 1949, Serial No. 109,879

1 Claim. (Cl. 273—130)

1
This invention relates to a game, and more particularly to a game of chance for playing by any number of persons, as at parties, clubs, lodges and the like.

It is an object of this invention to provide a game of this kind which is of such a nature that it may be played by any number of players, and each player will have an equal chance of scoring.

A further object of this invention is to provide a game of the kind to be more particularly described hereinafter, the norm or aim of which will be changed at each playing at the selection of the players. The players, after selecting a name to be determined, may select the positions on a scoring pad, at which they may believe or guess the various letters will occur as discs, having the letters of the selected name, are over-turned by a person directing the game.

With the above and other objects in view, my invention consists in the arrangement, combination and details of construction disclosed in the drawings and specification, and then more particularly pointed out in the appended claim.

In the drawings:

Figure 1 is a top plan view of the Key card used in the game of this invention;

Figure 2 is a perspective view of a pad of player cards to be used in the game;

Figure 3 is a top perspective view of one of the game pieces;

Figure 4 is a bottom perspective view of one of the blank game pieces;

Figure 5 is a perspective view of the bottom of one of the game pieces having alphabetical indicia thereon.

Referring to the drawings, the numeral 10 designates generally the Key card for a game formed according to an embodiment of this invention. The game is of the general type known as the game of Lotto or Bingo, but in the game of this invention, the name which provides the norm or aim may be varied each time the game is played.

The game is played with a Key card 10 which is to be handled by the Keeper of the game, a plurality of pads 11 to be handled by the players of the game, and a large number of playing pieces which will be handled by the Keeper to be placed on the Key card 10.

The Key card 10 is formed with a plurality of rows of blank spaces, preferably nine horizontal rows arranged in superposed relation, and six horizontal rows, the intersections of the horizontal and vertical rows defining a plurality of squares 12 on the Key card 10. As an ornamental

decoration on the Key card 10, the corner squares 14 will be colored, so that the squares 12 in the center portion of the card will be used as the board or ground on which the game pieces, to be described hereinafter, will be placed. The top row 15 and the bottom row 16 on the card 10 will define four blank playing spaces, whereas the intermediate horizontal rows 17 will extend entirely across the playing surface of the card.

10 The pad 11, to be used by each of the players, is formed with a plurality of playing cards or sheets of paper 18 having horizontal rows of squares or spaces 19 on the playing side thereof arranged in the same manner as the rows 15 and 17 on the Key card 10. The sheets 18 of the pad 11 will be secured together along one marginal edge thereof in a substantially conventional manner, not shown in the drawings, so that a sheet of carbon paper 20 may be inserted between selected ones of the sheets and preferably engaged below the uppermost sheet, as clearly shown in Figure 2 of the drawings.

15 A plurality of discs 21 are provided to be placed on the Key card 10 by a Keeper or director of the game, and certain of the cards 21 will be designated as blank discs 22, while other of the game pieces or discs will be designated as the alphabetical discs 24. For playing the game, each of the players is provided with a pad 11 having a plurality of sheets 18 thereon and the Keeper of the game is provided with a Key card 10. A name, either a common or a proper name is selected by some person, and that name will be written in the space 25 adjacent the upper margin of each of the player cards 18. The sheet of carbon paper 20 is then engaged below the upper player sheet 18 before the name is written on the top sheet, so that the name will also be written, as a carbon copy, on the second sheet.

20 25 30 35 40 45 The letters of the selected name are then chosen from a number of alphabetical playing pieces 24, and placed with a large number of blank playing pieces 22, the total number of game pieces 21 selected including the name selected spelled on the alphabetical cards 24 and sufficient blank discs 22 to cover each of the blank spaces 12 on the Key card are mixed together indiscriminately in such a manner that the lettered cards comprising the letters in the selected name may be placed at undetermined positions on the Key card 10.

45 50 55 The Keeper of the game then selects the mixed playing discs 22 and 24 and places them indiscriminately in the blank spaces 12 on the Key card 10. The discs 21, when placed on the Key

card 10, will be placed with their lettered sides downwardly so that all of the discs have the same appearance when viewed from above, as by the players playing the game.

The players then select those positions which they choose on their sheets 18, where they believe the various letters of the name will appear when the playing discs are overturned on the Key card 10. Each of the players then removes the top card from his pad and turns it in to the 10 Keeper of the game and will retain a carbon copy of his own for keeping his score.

The Keeper of the game then proceeds to overturn the playing discs on the Key card 10 by starting at the upper left corner and proceeding to the right in the top line and starting at the second and successive lines in the same manner. As the Keeper will also be unable to determine which of the playing discs 21 are the discs which have the letters on the lower sides thereof, and as the Keeper will also be unable to determine the position on the card where the different letters will appear, the score is determined by the guess or selection of the player.

As the blank discs 22 and the alphabetical discs 24 are promiscuously mixed together and distributed on the Key card 10, the score will be determined by the guess of the player as to the accurate positioning of the alphabetical cards when they are overturned on the Key card 10.

As noted above, the Keeper of the game will start turning the discs over for exposing the letters thereon from the upper left corner to the right of the Key card, and then will proceed in the same manner downwardly along the length of the card until all of the letters of the selected name have been overturned.

By mixing the lettered discs 24 with the blank discs 22, it is clear that the name, as it is turned up in the playing of the game, will not be spelled by the letters in their proper succession, so the players must select the position of the letters of the name irrespective of the relative position of the same letter in the proper spelling order of the name.

The score may be determined by the determination of the proper order in which the letters will appear and the score will also be determined by the proper line in which the various letters will appear. Preferably, the scoring is determined by letter scores and by line scores, the letter scores to be awarded for the determination of the right letter in the correct square, whereas the line scores will be determined by the selection of the correct letter in the proper line.

As an example of how the game will be played, if the selected name is "Charles," the Keeper of the game selects the suitable alphabetical letters 24 which will spell the name "Charles," and mixes these discs with enough of the blank discs 22 to fill all of the blank spaces 17 on the Key card 10. The blank discs 22 and the alphabetical discs 24 are then mixed together, and the Keeper will then place the mixed discs 21 on the Key card without looking at the alphabetical discs to determine, at that time, the proper positioning of the alphabetical discs. When the discs 21 are properly positioned on the Key card

10, all of the discs will look alike, being similar on the top, as clearly noted in Figure 3 of the drawings. The Keeper will then overturn the playing discs in the manner described above, and it will appear that the letter "h" will be the second disc which is overturned and the first letter. The Keeper will then look at the sheets 18 which have been turned in to him by the various players, to determine at that time which player has selected that position for the letter "h." Those players which have selected the proper line for the letter "h" may receive a certain score, and those players which have selected the proper space will receive another score which will be greater than the line score. The Keeper will then continue by overturning the discs 21 in each line on the Key card 10 until the whole name has been spelled. At this time, the entire score of each of the players may be readily determined.

I do not mean to confine myself to the exact details of construction herein disclosed, but claim all variations falling within the purview of the appended claim.

I claim:

In game apparatus, a key member comprising a rectangular game board having a playing surface having intersecting longitudinal and transverse lines thereon defining longitudinal and transverse rows of spaces, a plurality of player members comprising cards corresponding in number to the number of players involved, said player cards having surfaces provided with rows of spaces similar to the surface of said game board, and a multiplicity of game pieces adapted to be placed indiscriminately on the spaces of the game board surface, said game pieces including blank game pieces and lettered game pieces, each of the lettered game pieces having a blank face and a face formed with a single letter of the alphabet, lettered game pieces spelling a selected word selected from said multiplicity of game pieces being placed indiscriminately on spaces of the game board surface with their lettered faces down and the remaining spaces of the game board surface being covered by blank game pieces, the spaces of the player cards being arranged to be marked by the players to implement guesses as to the locations of the lettered game pieces, and the game pieces on the game board surface being arranged to be inverted after the player cards have been marked.

CHARLES S. HORINE.
